BOOT SOLE FOR FOOTBALL FOOTWEAR Raymond B. Lamarche, Beloeil, Quebec, Canada, assignee to The Acton Rubber Ltd., Acton Vale, Quebec, Canada

Filed July 31, 1972, Ser. No. 276,354

Term of patent 7 years

Int. Cl. D2—04

U.S. Cl. D2—320

Fig. 3

FIG. 1 is a top plan view of a boot sole for football footwear showing my new design; details of the boot sole shown in the section near the center being continuous;

FIG. 2 is an enlarged fragmentary view thereof; and

FIG. 3 is an edge view thereof which coincides with FIG. 1 and wherein, similarly, details of the boot sole shown in the section near the center are continuous.

I claim:

The ornamental design for a boot sole for football footwear, substantially as shown and described.
